CLAIM

The ornamental design for a television apparatus, as shown and described.

DESCRIPTION

FIG. 1 is a top perspective view of a television apparatus showing my new design;

FIG. 2 is a front view of the television apparatus shown in FIG. 1;

FIG. 3 is a right side view of the television apparatus shown in FIG. 1, the left side view being a mirror image thereof;

FIG. 4 is a rear view of the television apparatus as shown in FIG. 1;

FIG. 5 is a top view of the television apparatus shown in FIG. 1;

FIG. 6 is a bottom view of the television apparatus shown in FIG. 1; and,

FIG. 7 is a bottom perspective view of the television apparatus shown in FIG. 1.

The broken lines in the drawings are for the purpose of illustrating portions of the television apparatus that form no part of the claimed design.

1 Claim, 5 Drawing Sheets
